CONVEYER APRON

Coy E. Brittell, Chambers, Nebr.

Application February 13, 1941, Serial No. 378,791

1 Claim. (Cl. 198—199)

This invention relates to conveyer aprons for combines and similar devices, and has for the primary object the provision of a device of this character which will be more serviceable by increasing its span of life or usefulness over similar devices now in use which are easily damaged or made unfit for service due to the cleats or slats thereof which are secured in place by fasteners tearing loose within a short period of time.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawing, in which

Figure 1 is a top plan view illustrating a conveyer apron constructed in accordance with my invention.

Figure 2 is a transverse sectional view taken on the line 2—2 of Figure 1.

Figure 3 is a fragmentary longitudinal sectional view taken on the line 3—3 of Figure 1.

Figure 4 is a fragmentary perspective view illustrating one of the reinforcing strips.

Referring in detail to the drawing, the numeral 5 indicates as an entirety the apron consisting primarily of a sheet 6 of combined rubber and canvas having a selected width and length and has secured to one end thereof a series of straps 7 provided with apertures and secured to the opposite end of a plurality of buckles 8 for receiving the straps for connecting the sheet of material 6 into endless formation. To strengthen the longitudinal edges of the sheet of material 6 reinforcing elements 9 are secured thereto. The reinforcing elements 9 are constructed of the same material as the sheet 6 so that said reinforcing element and the sheet 6 can be moulded or vulcanized as of an integral construction.

Extending transversely and at spaced intervals of the sheet are cleats or slats 10 constructed of rubber which are moulded onto the sheet 6 and reinforcing members 9 forming the major part of this device of integral construction so that the life of the device will be materially increased over devices for a similar purpose now in use.

A flap 11 is provided at one end of the sheet 6 for covering the straps 7 and buckles 8 when the sheet is arranged in endless formation.

The slats are of rectangular shape in cross section, as shown in Figure 3, so as to readily gather material on the apron during the use thereof and the slats being vulcanized onto the sheet 6 as well as the reinforcing elements 9 will prevent said slats from tearing loose during the use of the device, consequently increasing the span of life of the device.

A device of this kind besides being durable may be manufactured and sold at a low cost.

While I have shown and described the preferred embodiment of my invention, it will be understood that minor changes in construction, combination and arrangement of parts can be made without departing from the spirit and scope of the invention as claimed.

Having thus described the invention, what I claim is:

In a conveyer apron, a vulcanized sheet of combined rubber and canvas, reinforcing strips of combined rubber and canvas moulded onto the outer surface of the sheet at the longitudinal edges thereof, rubber cleats of solid formation moulded onto the outer surface of the sheet, said cleats extending transversely of said sheet with their ends overlying the reinforcing strips and moulded thereto and arranged in spaced relation to each other and each being of substantially rectangular shape in cross section, and means for detachably connecting the ends of the sheet.

COY E. BRITTELL.
